UNITED STATES PATENT OFFICE.

TALIAFERRO J. FAIRLEY AND THOMAS M. DU BOSE, OF HATTIESBURG, MISSISSIPPI;
SAID DU BOSE ASSIGNOR TO SAID FAIRLEY.

PROCESS OF EXTRACTING PINE OIL, TURPENTINE, AND RESINOUS PRODUCTS FROM WOOD.

Application filed September 27, 1921. Serial No. 503,531.

To all whom it may concern:

Be it known that we, TALIAFERRO J. FAIRLEY and THOMAS M. DU BOSE, citizens of the United States, residing at Hattiesburg, ⁵ Forrest County, in the State of Mississippi, have invented certain new and useful Improvements in Processes of Extracting Pine Oil, Turpentine, and Resinous Products from Wood, of which the following is a full, ¹⁰ clear, and exact specification.

Our invention relates to improvements in the process of extracting certain of the constituent elements of wood by the destructive distillation thereof and the same has for ¹⁵ its object to provide a simple, convenient and efficient process for extracting pine oil, turpentine and other resinous products from wood in greater quantities than has heretofore been possible.

Further, said invention has for its object to provide a process by means of which the production or formation of the non-condensable gases occurring in the processes heretofore known will be wholly prevented, ²⁵ or so reduced in volume as to be negligible.

Further, said invention has for its object to provide a process which is simple to carry out, and by means of which the time necessary for the extraction of the pine oil, turpentine and other resinous products ³⁰ will be greatly shortened, and the cost correspondingly decreased.

Further, said invention has for its object to provide a process whereby a larger yield ³⁵ of pine oil, destructive turpentine and resinous products may be obtained.

Further, said invention has for its object to provide a process which may be carried out at such temperature as to carbonize the ⁴⁰ wood, and, after removing the excess pine tar oil, leave the carbonized wood sufficiently impregnated or saturated with pine tar oil to permit of the mixture being readily converted into briquettes so as to be ⁴⁵ available for fuel purposes.

Other objects will in part be obvious, and in part be pointed out hereinafter.

To the attainment of the aforesaid objects and ends, our invention consists in the process ⁵⁰ comprising the successive steps hereinafter more fully described and then pointed out in the claims.

The extraction of pine oil, turpentine and

other resinous products from wood has heretofore been accomplished by placing ⁵⁵ the wood into a closed receptacle having a suitable vapor outlet, and by the application of heat, either within or without the receptacle, cause the volatile fluids to be vaporized, and then separating the desired ⁶⁰ condensate from the remainder thereof; or by placing the wood in a receptacle and subjecting the same to a circulating bath of suitable temperature to extract the desired ⁶⁵ product, and then separating the same out of the bath, or by placing the wood in a receptacle and then extracting the desired products by the use of suitable solvents.

The said processes, however, all require long periods of time to carry out, ranging ⁷⁰ from thirty to forty-eight hours; yield but a comparatively small volume of the product desired; are all carried out at comparatively low temperatures, and in the case of the first and second named processes result in ⁷⁵ the production of gases which pass through all forms of condensers without being condensed.

Our process is principally distinguishable from the processes above specified in that ⁸⁰ the wood is disposed in a closed container and immersed in a liquid of high boiling point and then subjected to a high temperature which results in the destructive distillation of the wood; prevents the production of vapors which are not condensable; materially reduces the time required for the extraction of the pine oil, turpentine and other resinous products, and finally greatly increases the yield of said products ⁸⁵ over that obtained by other processes.

When destructive distillation of pine wood or the wood of any other tree occurs by the methods at present in use (without the presence of a body of oil surrounding ⁹⁰ and submerging the wood), it is accompanied by the formation of certain non-condensable gases, which pass through any or all forms of condensers as a gas or vapor without being condensed into a liquid. The ⁹⁵ percentage of these non-condensable gases may run as high as twenty per cent (20%) of the weight of the wood being treated. Now, according to our process with the oil body surrounding the wood in the retort ¹⁰⁰ no gases (or such a small amount as to be

negligible) are formed, that are not readily condensed into a liquid by any efficient type of condenser. This may be due to the catalytic action of the oils present by combining certain hydrocarbon groups with the so-called non-condensable gases, after they are formed, into carbon monoxide (CO), carbon dioxide (CO₂), methane (CH₄), and other complex mixtures of the so-called illuminants, having various groupings of carbon (C), oxygen (O) and hydrogen (H), or it may be due to the influence of the oils surrounding the wood chips in preventing the gases formed by the destructive distillation of the wood, from breaking up into non-condensable gases. Whatever the cause may be, however, the presence of the oils in contact with the wood, results in a decided increase in the amount of distillate formed in comparison with any other known process.

The accompanying drawing shows diagrammatically one form of apparatus for carrying out our process.

In carrying out our process of extracting pine oil, turpentine and resinous products from long leaf yellow pine and other resinous woods we proceed as follows:

The stumps and "down wood" are first subjected to the action of a "hog", or other suitable apparatus and reduced to chips or particles of the desired degree of fineness.

The chips are then placed in all metal cars or baskets 10, mounted upon wheels or rollers and introduced into a metal retort 11 which is so mounted in brick work that the same may be heated directly by fire disposed below the same, or preferably, as shown, by a closed steam coil 12 arranged upon or adjacent to the base of the retort 11. The retort is provided at both ends with hinged or removable doors or covers 13, which may be bolted to the ends of the retort so as to form fluid tight closures.

Pine tar oil, or a suitable mixture of pine tar oil, pine tar, pine oil and turpentine is then introduced from a source of supply 14 into the retort 11 by a pipe 15 connected to the top of the retort, in sufficient quantity completely to cover, when heated to a temperature of 600° F. or above, the charge of pine or other resinous wood chips in the retort. The pine tar oil or any mixture thereof, as hereinabove specified, may be introduced into the retort at atmospheric temperature, or it may be previously heated to any desired temperature. By using pre-heated oil the time for distilling the pine wood chips will be materially reduced. Where a plurality of retorts are provided the heated oil may be withdrawn by a pipe 20 from a retort in which the treatment of a charge of chips has been completed, and conducted to another retort containing a fresh charge of chips to be treated.

Saturated or superheated steam, as desired, is then admitted to the steam coils 12, which may be either closed or perforated, to heat the liquid in the retort, in order to vaporize the water, and volatile or volatilizable hydrocarbons present in the wood. The produced vapors are conducted by a collector 16 and pipe 17, extending from the top of the retort, to a condenser 18 of any suitable type and size whereby said vapors are efficiently condensed, and the condensate then conducted by a pipe 18^a to a suitable gravity separator 19 wherein the oils and lighter liquids will be separated from and floated upon the surface of the water.

When the retort attains a temperature of approximately 200 degrees Fahr. (which is the approximate boiling point of a mixture of water and turpentine), the first vapors are formed and condensed in their passage through the condenser, whence the same pass into and collect in the separator where the oily layer, which is lighter than the water, forms and floats on the surface of the water. At first the percentage of oil to water is small, and probably does not exceed five per cent of the water content by volume, but as the distillation proceeds the percentage of oils increases until only a trace of water is present in the condensate.

During the first part of the distillation the quantity of low specific gravity oils is much greater than that of the oils of high specific gravity, but towards the end of the distillation the reverse occurs, i. e. the higher specific gravity oils will predominate and only a trace of the low specific gravity oils will be present in the vapors coming over the retort.

While the distillation operation may be carried out within a period ranging from six to fourteen hours, and at temperatures ranging from 600 to 1200 degrees Fahrenheit, we find that the results may be best and most economically attained at a temperature of approximately 650 degrees Fahr., or such temperature as may be necessary not only completely to volatilize all the turpentine and pine oil present in the wood, but also efficiently to carbonize the wood.

When the specific gravity of the combined oils passing from the condenser shows that all pine oil and turpentine have been driven over, and other heavier products are being condensed, the steam supply is shut off from the coils, (or the fires drawn if the retort is being heated from without by fire). A valve 21 is then opened so that the original charge of pine tar oil, or any mixture thereof, pumped into the retort, plus a considerable volume of tar, given up by the destructive distillation of the wood may be drawn or by gravity into an auxiliary tank, or be pumped directly to the next retort.

containing a fresh charge of chips ready for treatment.

At this stage of the operation there will remain in the retort in the original fire-proof cars or baskets the charcoal thoroughly saturated with the original pine tar oil, plus some tar (formed by the destructive distillation of the wood) which remains behind in the oil, because the temperature within the retort was kept lower than that required to break the tar into tar oil. The end door or doors 13 of the retort 11 are now opened and the cars containing the oil soaked charcoal are rolled out, leaving the retort empty and ready to receive a fresh charge of chips.

The cars or baskets of oil soaked charcoal are then discharged into a storage hopper for delivery to a briquetting press of proper size to handle the charcoal, which, when freed from oil, amounts to approximately 400 lbs. per ton (2000 lbs.) of wood treated. During this operation ninety per cent (90%) of the oils present in the charcoal will be extracted, leaving the balance as a binder to cement the crushed charcoal particles together. The briquettes thus formed may be used for fuel, either in the plant boiler house or sold as fuel to the public.

The distillate from the condenser flows into a gravity separator 19, and inasmuch as water has a specific gravity of 1.000 at 60° F. in comparison with the heaviest weight oils formed during the immersion of the wood chips, with a specific gravity of under 1.000 at 60° F., the oil will float on top of the water layer, which latter is drawn off by a bottom connection. This water layer which, is sometimes called acid water or pyroligneous acid, actually contains a small amount of wood alcohol, and an average of approximately 4.0% acetic acid, both of which may be recovered if desired, but the recovery and refinement is not considered profitable at the present time.

By the destructive distillation processes heretofore known or used only an average of less than sixty (60) gallons of crude distillate per ton of wood treated could be produced of which less than eight (8) gallons is turpentine and less than five (5) gallons is pine oil, while by our process 55 gallons is pine oil, while by our process hereinabove described the oils, known as "crude oils," are produced in an amount equal to eighty (80) gallons per ton of wood treated, which, when refined will yield about eleven (11) gallons of wood turpentine, or oils having a specific gravity under .875, twenty-six (26) gallons of pine oil, or oils having a specific gravity under .940 and forty-three (43) gallons of tar, which last named, may be broken down into pine tar oil, if desired.

Having thus described our invention what

we claim and desire to secure by Letters Patent is:

1. The process of extracting pine oil, turpentine and resinous products from wood which consists in reducing the wood to chips, immersing said chips in a closed container in a liquid consisting essentially of oils of the terpene series, subjecting the mass to a temperature of about six hundred degrees Fahrenheit, to effect the destructive distillation of the wood and to convert the volatilizable constituents of the wood into condensable fluids, condensing said fluids, and finally separating the aqueous layer from the oleaginous constituents of the condensate, substantially as specified.

2. The process of extracting pine oil and turpentine from wood which consists in reducing the wood to chips, immersing said chips in a closed container in a liquid consisting essentially of pine tar oil, subjecting the mass to a temperature of six hundred degrees Fahrenheit, to effect the destructive distillation of the wood and to convert the volatilizable constituents of the wood into condensable fluids, condensing said fluids, and finally separating the pine oil, turpentine and resinous matter from the aqueous layer of the condensate, substantially as specified.

3. The process of extracting pine oil, turpentine and resinous products from wood which consists in reducing the wood to chips, immersing said chips in a closed container in a liquid consisting essentially of pine tar oil, subjecting the mass to a temperature of six hundred degrees Fahrenheit for a period of approximately six to fourteen hours to effect the destructive distillation of the wood and to convert the volatilizable constituents of the wood and said liquid into condensable fluids, condensing said fluids, and finally separating the pine oil, turpentine and resinous matter from the aqueous layer of the condensate, substantially as specified.

4. The process of extracting pine oil, turpentine and resinous products from wood which consists in reducing the wood to chips, immersing said chips in a closed container in a liquid consisting essentially of pine tar oil, subjecting the mass to a temperature of six hundred degrees Fahrenheit for a period of approximately six to fourteen hours to effect the destructive distillation of the wood and to convert the volatilizable constituents of the wood into condensable fluids, condensing said fluids, and finally separating the pine oil, turpentine and resinous matter from the aqueous layer of the condensate, substantially as specified.

5. The process of extracting oils of the terpene series from wood which consists in reducing the wood to chips, immersing and subjecting said chips in a closed container to the action of a catalytic agent con-

taining an element of a carbonaceous character subjecting the mass to heat to effect the destructive distillation of the wood and to convert the volatilizable constituents of the wood into condensable fluids, condensing said fluids, and finally separating said oils from the aqueous layer of the condensate, substantially as specified.

6. The process of extracting pine oil, turpentine and resinous products from wood which consists in reducing the wood to chips, immersing and subjecting said chips in a closed container to the action of a liquid containing an element of a carbonaceous character and serving as a catalytic agent, subjecting the mass to heat to effect the destructive distillation of the wood and to convert the volatilizable constituents of the wood into condensable fluids, condensing said fluids, and finally separating the pine oil, turpentine and resinous matter from the aqueous layer of the condensate, substantially as specified.
